UNITED STATES PATENT OFFICE.

NATHAN CORNISH, OF GARNER, IOWA.

ATTACHMENT FOR STRAW-STACKERS.

SPECIFICATION forming part of Letters Patent No. 561,093, dated June 2, 1896.

Application filed May 13, 1895. Serial No. 549,210. (No model.)

To all whom it may concern:

Be it known that I, NATHAN CORNISH, a citizen of the United States of America, residing at Garner, in the county of Hancock and State 5 of Iowa, have invented a new and useful Attachment for Straw-Stackers, of which the following is a specification.

The object of this invention is to provide a simple, cheap, and durable device adapted 10 to be attached to the lower end of the straw stacker or conveyer to separate from the straw, after it has passed through a thresher, any weed-seeds or grain that may have remained with the straw in its passage through 15 the thresher.

My invention consists in the construction, arrangement, and combination of the various parts of the device with a straw-stracker having an endless conveyer therein, as hereinabove set forth, pointed out in my claims, and 20 illustrated in the accompanying drawings, in which—

Figure 1 is a vertical longitudinal sectional view of the complete device applied to a straw-stack and connected with a thresher. Fig. 2 is a side view of the lower end of a stacker having the attachment thereon. Fig. 3 is a detail perspective view of one end of the shaft for supporting the auxiliary conveyer. Fig. 4 is a detail perspective view of the device for directing the air-blast from the fan, and Fig. 5 is a top or plan view of the upper or grain sieve.

Referring to the accompanying drawings, 35 the reference-letter A is used to indicate the frame of the straw-stack, having a roller A² mounted in one end and an endless conveyer A³ passed over said roller. These parts are all of the ordinary construction, and the 40 under part of said endless conveyer is held downwardly by means of a roller A⁴, supported by the brackets A⁵, to admit the mechanism hereinafter described between the stacker-frame and the endless conveyer.

B indicates a short endless conveyer mounted in the stacker-frame directly above the lower end portion of the endless conveyer A³ and composed of belts B² and cross-pieces B³, said belts being passed over the pulleys B⁴, 45 which in turn are placed on the end of the shaft B⁵. Said shafts are supported by means of brackets B⁶, secured to the stacker-frame

A, and each pair has a sleeve B⁷ formed integral therewith and having one of said shafts passed therethrough to prevent the straw 55 from being wound upon the shafts.

In the central portion of the conveyer B a shaft C is mounted, and on this shaft an irregular-shaped disk C² is mounted in engagement with the upper portion of the conveyer-belt, so that as the belt is operated said disk will constantly agitate the conveyer. A like disk is preferably placed on each side. The straw from the threshing-machine falls upon this conveyer, and all of the grain, seeds, &c., 60 are shaken from the straw and pass through the auxiliary conveyer to the main conveyer-frame.

D indicates a platform, mounted in the conveyer-frame between the upper end of the auxiliary conveyer and the conveyer proper, to carry any grain or weed-seeds that may pass through the upper end of the auxiliary conveyer to a point below the grain-sieve in the bottom of the stacker and also to prevent the 70 air-blast through the sieve from blowing the straw upwardly against the auxiliary conveyer.

F indicates a sieve slidingly mounted in an opening in the bottom of the straw-stack beneath the platform D and adapted to be moved during the operation of the conveyer by means of a crank-arm F², secured to one end of the upper shaft B⁵ and connected with the sieve by means of a rod F³.

F⁴ is a sieve having a mesh that will not admit grain, (but which will readily pass weed-seeds, &c.,) situated over an opening in the stacker-bottom at a point below the sieve F.

H indicates a sheet-metal casing, cylindrical at H² and containing a fan H³. Its ends extend to the upper and lower ends of the sieve F, and at H⁴ it is curved backwardly to direct the blast backwardly and upwardly through the sieve.

J indicates a chute leading from the interior of the fan-casing above the cylindrical part, approximately V-shaped in transverse section and inclined downwardly toward one side of the machine, with a spout J² connected therewith. The grain passing through the upper sieve will fall upon the bottom of the chute J and be carried to the said spout J².

J³ indicates a deflector secured to the sides

of the fan-easing and curved forwardly and downwardly from a point a slight distance above the top of the chute to direct a portion of the air-blast from the fan downwardly into 5 the chute J and spout J².

J⁴ and J⁵ indicate deflectors placed beneath the sieve to direct portions of the air-blast upwardly through the sieves at various points, so that the air-blast will be distributed approximately equitably throughout the entire 10 sieve, thus holding the chaff above the sieve and permitting the grain to pass therethrough.

J⁶ indicates openings in the side of the fan-easing for the admission of air, and J⁷ are 15 hinged covers therefor, whereby the draft may be regulated.

K indicates a chute leading from the sieve F⁴ downwardly and forwardly to the fan-easing, having a small opening K² communicating 20 with said easing. In the bottom of the chute K is an opening K³, made by cutting the metal transversely of the stacker and bending the part thus formed upwardly. Thus all 25 of the grain passing into the chute will be directed through said opening and the air-blast be permitted to pass upwardly through the sieve.

The fan and also the auxiliary conveyer are operated from the shaft of the endless conveyer by means of the sprocket-gearing N, as 30 clearly shown in Fig. 2.

In practical operation it will be obvious that as the chaff and straw are discharged from the threshing-machine they will fall upon the auxiliary conveyer, which by being constantly agitated will permit the grain, weed-seeds, &c., to pass through, while the bulk of the straw will be carried upwardly over the conveyer proper. All of the matter passing 35 through the auxiliary conveyer will be carried downwardly below the grain-sieve by the platform above the sieve and be carried up over the sieve by the conveyer proper. Weed-seeds and other small particles will pass 40 through the lower sieve and grain will pass through the upper sieve, the straw and chaff being held from the sieve by the air-blasts from the fan. The blast will be directed by 45 the deflector within the easing downwardly through the chute and spout, thus forcing the 50

grain through the spout, even though it should be wet or clogged by other obstacles.

Having thus described my invention, what I claim as new therein, and desire to secure by Letters Patent of the United States therefor, 55 is—

1. The combination with a straw-stacker or the like, having a solid bottom, an endless conveyer arranged to travel over said bottom and a sieve in the bottom, of a fan arranged when 60 operated to produce an air-blast upwardly through said sieve, an apron beneath the sieve having a curved partition to protect it from the air-blast proceeding from the fan, a grain-discharge chute leading from the apron and 65 a deflector above the apron to direct part of the air-blast through said grain-chute, substantially as set forth.

2. The combination with a straw-stacker having a solid bottom and an endless conveyer thereon, of an auxiliary conveyer composed of belts and cross-slats, mounted in said frame above the lower end thereof, irregular-shaped idlers to engage said belts and agitate the conveyer, two sieves in the bottom of the 70 stacker-frame, a platform above the upper one and means for supplying an air-blast upwardly through said sieves, for the purposes 75 stated.

3. An attachment for straw-stackers, comprising an auxiliary conveyer, mounted in the lower end portion of the stacker-frame above the conveyer proper, irregular-shaped idlers under said conveyer, a platform beneath the end of the auxiliary conveyer, a sieve in 80 the stacker-bottom, a second sieve slidably mounted therein, means for operating said sliding sieve, a fan-easing beneath the stacker-frame, a fan therein and means for operating said fan, a chute therein, a curved deflector 85 above the chute, deflectors beneath the sieve and a chute leading from the fan-easing to the lower sieve and having an upwardly-bent portion in its bottom, substantially as and for the 90 purposes stated.

NATHAN CORNISH.
